UNITED STATES PATENT OFFICE

101,518

DESIGN FOR A HOTEL REGISTER

Richard Cooper, Columbus, Ohio

Application May 6, 1936, Serial No. 62,509

Term of patent 3½ years

To all whom it may concern:

Be it known that I, Richard Cooper, a citizen of the United States, residing at Columbus, in the county of Franklin and State of Ohio, have invented a new, original, and ornamental Design for a Hotel Register, of which the following is a specification, reference being had to the accompanying drawing, forming part thereof.

In the drawing, Fig. 1 is a top plan view of a hotel register, showing my new design; Fig. 3 is a top end view of Fig. 1; Fig. 2 is a right hand side view of Fig. 1; and Fig. 4 is a bottom end view of Fig. 1.

I claim:

The ornamental design for a hotel register, as shown.

RICHARD COOPER.
